THERMIC SIPHON

Gust J. Christenson, Chicago, Ill., assignor to
 Locomotive Firebox Company, Chicago, Ill., a
 corporation of Delaware

Application January 3, 1939, Serial No. 248,977

4-Claims. (Cl. 122—68)

This invention relates to improvements in thermic siphons and it consists of the matters hereinafter described and more particularly pointed out in the appended claims.

In any firebox of the locomotive boiler type, there is some movement of the roof and crown sheets under the temperature and pressure conditions which obtain in use. These movements manifest themselves as deflections or distortions of the sheets and generally increase with pressure and temperature. The magnitude of the deflection is also dependent upon the character of the metal employed, i. e. whether of plain carbon steel or of so-called low alloy, high tensile strength steel.

It is possible to obtain sufficient tensile strength with a thinner alloy steel sheet for a given pressure than with a plain carbon steel sheet but deflection in certain directions will be greater with the thinner low-alloy high tensile strength steel than with the relatively thicker, plain carbon steel necessary to provide an adequate or like tensile strength.

The demand for more power per unit, especially in locomotive boiler practice, has forced the use of higher pressures and larger and longer locomotives. Because of roadway limitations, both as to clearances and as to load supporting capacity, it is desirable, especially in the larger type locomotives to use the thinner sheets of alloy steel rather than the thicker sheets of plain carbon steel. This is true even though the use of such relatively thin alloy steel sheets results in greater movement or deflection of the firebox sheets which in the larger locomotives is of a relatively high order.

One object of the present invention is to provide a thermic siphon of such construction that it is better adapted for use in fireboxes, when the size of the firebox, pressure conditions and the relative thinness of the steel sheets thereof are such as normally to result in a very considerable movement or deflection of the sheets of the firebox.

Again, it is an object of the present invention to provide a thermic siphon of such construction that it more readily adapts itself for use in long fireboxes of the locomotive boiler type and more effectively rigidifies the crown sheet for resisting movement thereof than is possible in siphons as heretofore made.

Another object of the invention is to provide a thermic siphon of such a construction that a longer body may be used and hence greater heat transmission obtained in longer fireboxes, with-

out the danger of the movement of the crown sheet effecting a movement detrimental to the top end of the siphon body.

A further object of the invention is to provide a thermic siphon structure, which permits of a better support of the non-self supporting wrapper or roof sheet of the boiler, from the crown sheet, by making it possible to employ more staybolts therebetween.

10 Still another object of the invention is to provide a thermic siphon of this kind wherein it is possible to impart a better forward directional movement to the water discharged from the outlet of the siphon into the boiler water space above the crown sheet.

15 Still a further object of the invention is to provide a siphon of this kind which is so constructed as to provide better conditions for working upon staybolts in the crown sheet at a point between the front and rear ends of the siphon.

Again, it is a further object of the invention to provide a siphon having a body which permits of a lateral movement of the products of combustion through the body of the siphon so as to 20 equalize flame spreading throughout the upper portion of the firebox, and thus reduce strains due to unequal heating of certain of the firebox sheets.

The above mentioned objects of the invention 25 as well as others together with the advantages thereof will more fully appear as the specification proceeds.

In the drawings:

Fig. 1 is a longitudinal vertical sectional view 30 through the firebox end of a locomotive boiler embodying the preferred form of the invention.

Fig. 2 is a transverse vertical sectional view 35 through the firebox end of the boiler as taken on the line 2—2 of Fig. 1.

Fig. 3 is a horizontal detail sectional view 40 through the construction shown in Fig. 1 as taken on the line 3—3 of Fig. 1.

Fig. 4 is a view similar to Fig. 3 but illustrates 45 a modified form of construction which will more fully be described later.

Fig. 5 is a fragmentary view in side elevation 50 of the upper central portion of a modified form of siphon structure which will be described in more detail later.

Fig. 6 is a top plan view of the parts appearing in Fig. 5.

Fig. 7 is a vertical sectional view through that 55 form of the invention appearing in Fig. 5 as taken on the line 7—7 of Fig. 5.

Referring now in detail to that embodiment

of the invention illustrated in the accompanying drawings and more especially to Fig. 1 thereof, the firebox of the locomotive boiler type therein shown and which is a relatively long one, comprises a flue sheet 10, rear sheet 11, crown sheet 12 and side sheets 13, the bottom portion of the flue sheet forming the inner throat sheet 14. All of said sheets are arranged in the manner found in fireboxes of this kind. 15 indicates the barrel of the boiler, 16 the top part of the wrapper sheet thereof and 17 and 18 indicate the outer throat sheet and the back sheet thereof respectively.

The sheets 16-17 and 18 coat with the conventional outer side sheets 19 in providing the usual side water legs 20, the front throat 21 and back water leg 22 respectively, all bottomed by a mud ring 23 as appears in Figs. 1 and 2. In the boiler shell are the flues which extend forwardly from the flue sheet toward the usual smoke box. 24 indicates the fuel door opening formed by coacting parts of the sheets 11 and 18 respectively. The construction above described, which of course is staybolted in the usual manner may well be taken as typical of that found in boilers of the locomotive type now in general use.

To increase the water steaming and circulating efficiency of such boilers, additional heating elements are employed in the firebox and such elements usually draw boiler water from a water leg or other point toward the bottom of the boiler and discharge the same through the crown sheet. By way of example only, I have illustrated a construction in which the intake is at the front water leg.

In relatively wide fireboxes, usually more than one siphon is employed therein and these are spaced apart laterally in the firebox, one on each side of the longitudinal median plane of the boiler and firebox as a whole as appears in Fig. 2.

In Figs. 1 and 2, the siphon is indicated as a whole by the numeral 25. It comprises a flat hollow body 26 of a somewhat triangular shape, and a tubular inlet neck 27. The siphon body includes spaced side walls 28-28 (see Fig. 2) front and rear end walls 29 and 30 respectively and a downwardly bulged bottom portion 31 that merges into the neck 27 and is connected by a rounded corner or nose 32 with the rear wall 30. The side walls 28-28 of the body are operatively connected together by the staybolts 28a. The front and rear walls are inclined downwardly and inwardly and the front wall 29 joins the top rear end portion of the neck 27 by an inside rounded corner or junction 33. It is apparent that a considerable portion of the front end of the body overhangs the neck and this overhang forms a pocket which appears to the right hand side of the vertical line A-A appearing in Fig. 1.

In the upper central portion of the body an opening 34 is formed, which divides the upper or top end of the body into front and rear end outlets 35 and 36 respectively which are spaced apart longitudinally of the body. Each outlet 35-36 as best appears in Figs. 1 and 2 has its own individual flanged top end 37 and 38 respectively and each flange is fitted and welded in place in a corresponding opening in the crown sheet as indicated at 39 and 40 respectively. The front end of the tubular inlet neck 27 engages and is welded in a diaphragm opening 41 in the front throat sheet 14 of the firebox.

It is apparent from Figs. 1 and 2 that the opposite adjacent ends of the flanges 37-38 are

spaced apart by a portion of the crown sheet and which portion is indicated by the numeral 42 in Figs. 1 and 3. With such an arrangement it is possible directly to connect and support that part of the wrapper sheet 16 above said crown sheet part 42 with said crown sheet part by means of some of the radial stays 43. Thus the crown sheet is continuous, transversely considered, across the top of the firebox at this point.

If desired, instead of providing a separate flange about the top end of each outlet, a flange 44 common to both outlets 35-36 may be employed, and this arrangement is shown in Fig. 4.

The opening 34 is of substantially an elongated oval shape, so that its bottom 34a curves upwardly in opposite directions to merge into the rounded ends 34b and 34c respectively and which ends in turn merge into the opposed adjacent ends of the flanges 37-38. The vertical depth of said opening is made of such dimension as to provide sufficient room for tools used from inside the firebox, in upsetting those radial staybolts 43 disposed in said crown sheet part 42.

As the water leaves the inner or rear end of the neck 27 and enters the body 26, the curved bottom and the rounded ends of the opening 34 function to deflect the water and steam bubbles into the respective outlets. The rounded end 34b of said opening also directs or deflects a part of the water forwardly into the pocket produced by the overhang of the front end of the body as before described. This accelerates circulation of water upwardly along the inner face of the front end of the body to assure sufficient water forwardly of the front outlet in case of low water conditions so that flooding of the higher front end part of the crown sheet is assured even under such adverse conditions.

With the improved siphon construction, when crown sheet movement occurs under service conditions, it is apparent that the use of the longitudinally spaced outlet openings, that are separated by an integral or by a welded in part of the crown sheet, a greater resistance is afforded to the tendency of the transmission of lateral spreading movement of the crown sheet to the top end of the siphon body. Thus tighter connections are afforded for the siphons in the crown sheet, without leakage under service conditions over longer periods of time.

While the arrangement above described may somewhat reduce the area of the outlet opening of the siphon body as a whole and may therefore seem undesirable, the division of the single outlet into a plurality of outlets of lesser area has several advantages which, nevertheless make this arrangement more desirable and practical. Such an arrangement braces the upper central portion of the body against spreading tendency, eliminates the blind or quiescent pocket at the front end of the body by increasing circulation therein and assures sufficient water forwardly of the siphon to flood the front end of the crown sheet even under low water conditions.

In Figs. 5-6 and 7 I have illustrated a modified form of the invention, which may be embodied in a siphon in the course of its manufacture or by which a long bodied siphon, already in service, may be converted into one embodying the present invention.

In accordance with said modified form of the invention, central portions of both side walls 26a-26a of the body are cut away to form recesses therein, each defined by straight vertical front and rear ends 45 and 46, and an upwardly

curved bottom 47 that merges at its ends into rounded corners 48 which in turn merge into said straight vertical ends. In the bottom portion of the recess thus produced, I provide an insert made of two plate-like parts 49-49 each having outer edges, butt welded as at 50 in the major bottom portion of the openings in the siphon body side walls 26a-26a. The inner edges of the plate-like parts are rounded over toward each other to be welded together as shown at 51 in Fig. 7.

52 indicates a plate-like crown sheet portion of substantially elongated rectangular form that fits and is welded in an opening provided therefor in the crown sheet 12a. The central end portions of this plate-like crown sheet portion are each flanged downwardly as at 53 and these portions each register at the bottom edges with the top end edges of the plates 49. These portions also register at their end edges with that part of the side walls of the siphon body above the top edge of the plates 49. The before-mentioned edges are welded as shown at 54 to those edges with which they have engagement.

It is apparent that the inner ends of the flanges 53 form continuations of the curved portions of the plate members 49 to define the top part of the opening 34d. The plates 49-49 are staybolted together as appears in Fig. 5.

The above construction is especially useful in converting a long, single outlet siphon body, already in service, into one with more than one outlet and having the advantages hereinbefore mentioned.

While in describing my invention I have referred in detail to the form, arrangement and construction of the parts thereof, the same is to be considered only in the illustrative sense so that I do not wish to be limited thereto except as may be specifically set forth in the appended claims.

I claim as my invention:

1. In a firebox of the locomotive boiler type having a crown sheet, a longitudinally positioned, mainly flat water steaming and circulating element in the firebox embodying side walls and front and rear end walls, the top portion of the body being fixed in the crown sheet to open therethrough, a tubular neck connecting the bottom portion of the body with the water space in the lower part of the boiler, the front end wall of the body extending downwardly and inwardly toward the junction of said neck with the body, so that the upper front end portion of the body overhangs a part of said neck, and means forming at least one elongated opening

5 of considerable area through the upper central portion of the body adjacent the crown sheet, said means having its front portion so disposed with respect to the before-mentioned junction as to deflect a part of the incoming and upwardly rising water from said junction into the overhanging front end portion of the body for discharge into the boiler water space above the crown sheet.

2. In a firebox of the locomotive boiler type having a crown sheet, a longitudinally positioned water wall in the firebox including a mainly flat hollow body, means providing at least one opening of substantial area through the upper central portion of the body adjacent the crown sheet to provide a plurality of longitudinally spaced outlets for said body, which are welded in and open through the crown sheet into the steam and water space of the boiler above said crown sheet, and a tubular inlet neck connecting the bottom portion of the body with the boiler water space in the lower part of the boiler.

3. In a firebox of the locomotive boiler type having a crown sheet, a longitudinally positioned water wall in the firebox including a mainly flat hollow body, means providing at least one opening of substantial area through the upper central portion of the body adjacent the crown sheet, and having a major dimension in the direction of the length of the crown sheet and a minor dimension in a direction substantially perpendicular to the crown sheet, said opening dividing the upper portion of the flat hollow body into a plurality of longitudinally spaced outlets therefor which are welded in and open through the crown sheet into the steam and water space of the boiler above said crown sheet, and a tubular inlet neck connecting the bottom portion of the body with the boiler water space in the lower part of the boiler.

4. In a firebox of the locomotive boiler type having a crown sheet with a plurality of longitudinally extending openings therein separated from each other by a crown sheet portion, a longitudinally positioned water wall in the firebox including a mainly flat hollow body, there being an opening of substantial area through the upper central portion of the body adjacent the crown sheet to provide a plurality of longitudinally spaced outlets for said body, which are welded in said longitudinal openings, said opening in said body being closed at the top by said crown sheet portion, and a tubular inlet neck connecting the bottom portion of the body with the boiler water space in the lower part of the boiler.

GUST J. CHRISTENSON.
